UNITED STATES PATENT OFFICE.

JOHN HERBERT VEASEY, OF JOHANNESBURG, TRANSVAAL, SOUTH AFRICA.

FLUID-PRESSURE-ACTUATED CLAMP PARTICULARLY FOR ROCK-DRILL MOUNTINGS.

1,404,179.

Specification of Letters Patent. Patented Jan. 17, 1922.

Application filed November 26, 1919. Serial No. 340,823.

To all whom it may concern:

Be it known that JOHN HERBERT VEASEY, a British subject, residing at 44 Anstey's Buildings, Kerk Street, Johannesburg, 5 Transvaal Province of the Union of South Africa, has invented certain new and useful Improvements in Fluid-Pressure-Actuated Clamps Particularly for Rock-Drill Mountings, of which the following is a specification.

The present invention relates to clamping devices actuated by fluid pressure and particularly to such devices embodied in mountings for rock drills. In the specification of 15 my Transvaal Patent No. 269/15, I have described a rock drill arm which is secured to its column by a hydraulic clamp, and also a hydraulic clamp for securing the drilling machine to the arm. In these constructions 20 a cylinder and a plunger were employed; and when using low pressure fluid these parts become somewhat bulky.

It is the object of the present invention to provide an improved construction which 25 is lighter, less bulky and cheaper than those employing a cylinder and piston and in which the pressure area can be varied without undue expense.

According to the present invention the 30 clamping and unclamping movement is attained by means of a flexible diaphragm exposed to the fluid pressure. A small movement of the diaphragm is sufficient to apply or relieve the tightening pressure; if 35 further adjusting movement is required it may be attained by manually actuated mechanism such, for instance, as a cam, bolt and nut, or the like.

The diaphragm may be formed of any 40 suitable flexible material such as rubber fabric, leather and the like in which case a pressure plate may be interposed between the diaphragm and the part onto which it presses in order to protect it from damage. 45 A corrugated or other flexible metal plate may also be used and may itself form the pressure plate or it may be provided with a separate pressure plate.

In the accompanying drawings, 50 Fig. I shows one form of the improved clamp secured to an arm.

Fig. II is a partial plan of Fig. I.

Fig. III shows a modified construction of 55 the clamp, employed for securing an arm to a column.

Fig. IV is a cross sectional view of the

clamping plate of Fig. III, drawn to an enlarged scale.

Referring to Figs. I and II, 1 indicates the foot of a rock drilling machine, and 2 60 an arm to which the rock drilling machine is to be clamped.

The clamp consists of the two jaw elements 3 and 4. The parts of the clamp are connected by bolts 5 which also serve to 65 grip the foot 1 and so secure it to the jaw element 3.

The pressure element comprises a metal frame comprising a back plate 6 and side walls. It is conveniently formed from sheet 70 metal by first cutting it to shape and then bending up the side walls from the back 6 so as to form first an upstanding wall 7 all around, then an inturned flange 8, and then an upturned flange 9; said parts 7, 8 75 and 9 being welded together at the corners 10. A flexible diaphragm 11 is pressed into the recess 12 formed between the back plate 6, the wall 7, and the flange 8, so making a joint with the frame all around 80 its edge. A loose pressure plate 13 is dropped into the recess bounded by the upstanding flanges 9 and is retained in place by suitable stops indicated by 14. The pressure plate 13 makes contact with the 85 jaw member 4.

At the back of the pressure member is a cross bar 15 to which the bolts 5 are pivotally secured; the head ends of these bolts being passed into place through recesses 16 90 formed in the jaw member 3. 17 is a connection by which fluid under suitable pressure is conveyed between the plate 6 and the flexible diaphragm 11.

In operation the clamp members are 95 arranged in position as shown and upon pressure fluid being admitted through the connection 17 the diaphragm is forced outwards, taking with it the pressure plate 13 and the jaw 4, and so forcing the clamp 100 members together.

In the modified construction shown in Figs. III and IV the positioning of the clamp members is effected by other than the fluid pressure means and said means is 105 employed simply to produce the final tightening pressure. Since in this case the movement of the diaphragm can be kept within a very small limit, practically the whole area of the diaphragm can be kept 110 always in contact with the part against which it presses, the pressure plate is dis-

pensed with and the diaphragm is permitted to bear directly against the member, in this case the column on which it grips.

In these drawings 18 indicates a column to which the arm 2 is clamped. On the arm is formed one element 19 of the clamp. From said part 19 extend bolts 20 carrying a cross shaft 21. Said shaft 21 rotatably supports a cam 22 provided with a handle 23. Said cam 22 bears against a bearing plate 24 on the back of the pressure member 25 so that by rotating the cam the pressure member can be brought into contact with the column 18.

15 The pressure member itself consists of a single plate 25 curved to fit the column 18. The flexible diaphragm 11 is held in place by turning over the edges 26 of the plate 25. A water connection 27 is fixed at 28 (Fig. 20 I) to deliver pressure water behind the diaphragm; the clamping operation being effected in this case as in the first example.

In order to hold the flexible diaphragm clear of the column when the diaphragm is slackened there may be fitted one or more thin flat springs 29 which are shaped to conform to the surface of the diaphragm and are clipped at their edges around the edge of the plate 25.

30 It will be seen in both of the above examples that owing to the rectangular shape of the pressure member and the narrow dead edge of the same, a considerable effective pressure area can be obtained with a pressure device of moderate size. If it is desired to vary the pressure area this can be done by lengthening or shortening the pressure member without otherwise varying its shape.

I claim.

40 1. A fluid pressure actuated clamp suitable for rock drill mountings, comprising a flexible diaphragm having a narrow confined edge and arranged for movement to apply clamping pressure and means to apply pressure fluid to one face of the diaphragm to effect such clamping movement.

2. A fluid pressure actuated clamp suitable for rock drill mountings, comprising a frame, a flexible diaphragm inserted into the frame and having a narrow edge clamped therein and means to apply fluid pressure between the back of the frame and the diaphragm.

3. A fluid pressure actuated clamp suitable for rock drill mountings, comprising a

frame, a flexible diaphragm mounted in the frame and having a narrow edge secured therein, a movable pressure plate in front of the diaphragm and means to apply pressure fluid to the other side of the diaphragm.

4. A fluid actuated clamp suitable for rock drill mountings, comprising relatively movable clamp elements, a flexible diaphragm associated with one of said clamp elements and arranged for movement to apply clamping pressure, said diaphragm having a narrow edge only confined, means to apply pressure fluid to a face of said diaphragm to effect such clamping movement and additional mechanism for producing relative movement of the clamp members.

5. The combination with a rock drill arm, of a drill carrying clamp comprising two clamp elements connected against separating movement, a flexible diaphragm associated with one of said clamp elements, and means to apply fluid pressure behind said diaphragm, the diaphragm moving under the influence of the fluid pressure to cause the clamp element to grip the arm.

6. The combination with a rock drill arm, of a clamp device constructed simultaneously to grip the arm and to secure a rock drill to the clamp, a flexible diaphragm for actuating the clamp and means to apply fluid pressure to the diaphragm to move the same for that purpose.

7. A rock drill arm clamp, comprising two clamp elements adapted to grip a drill arm between them, and one of said elements affording a seating for a drill foot, connecting means extending for the other clamp element and constructed to engage a drill foot positioned on said seating, a flexible diaphragm embodied in the clamp structure and adapted to move to tension said connecting means and means to apply fluid pressure to the diaphragm so to move it.

8. A rock drill arm clamp comprising two jaw elements adapted to grip the arm between them, a cross member, bolts extending from said cross member and shaped at their free ends to engage a drill foot with the opposite jaw element and a pressure element between the cross member and the adjacent jaw element comprising a flexible diaphragm and means to supply fluid pressure thereto.

In testimony thereof I affix my signature.

JOHN HERBERT VEASEY.
